Des. 210,274

Patented Feb. 27, 1968

210,274

NESTABLE STACKABLE TOTE TRAY OR SIMILAR ARTICLE

James D. Wilson, Long Beach, Calif., assignor to Banner
Metals, Inc., Compton, Calif., a corporation of Ohio

Filed Aug. 24, 1965, Ser. No. 86,728

Term of patent 14 years

(Cl. D9—242)

Fig. 1

Fig. 2

Fig. 3

Fig. 4

FIGURE 1 is a front perspective view of a nestable stackable tote tray or similar article showing my new design;

FIGURE 2 is a rear elevational view thereof;

FIGURE 3 is a bottom view thereof; and

FIGURE 4 is a side view thereof.

The side opposite to that shown in FIGURE 4 is the same as that shown in FIGURE 4.

I claim:

The ornamental design for a nestable stackable tote tray or similar article, substantially as shown and described.
